UNITED STATES PATENT OFFICE

2,325,256

FLUID-OPERATED PUMP

Roy E. Leonard, Alhambra, Calif.

Application June 23, 1941, Serial No. 399,316

4 Claims.

(Cl. 103—5)

This invention relates to pumps and more particularly to fluid-operated pumps for pumping wells, such as oil wells, and it is an improvement on my fluid-operated pump covered by my Patent No. 2,113,213.

The general object of the invention is to provide an improved pump of the character stated which is positive and highly efficient in operation.

Another object is to provide a pump of the character stated with means for allowing gas from below the packer at the lower end of the pressure chamber to enter the pressure chamber and operate the pump.

Other objects and advantages will appear hereinafter.

The invention is illustrated in the annexed drawings which form a part of this specification and in which,

Fig. 1 is a fragmentary vertical section of my pump illustrating one of the pump units.

Fig. 2 is a fragmentary vertical section of the lower portion of my pump, including the packer in the well at the lower end of the pressure chamber, in which packer the lower end of the pump is secured so that the pump may lift fluid from the bottom of the well through said packer.

Fig. 3 is a horizontal section of one of the pump units taken on line 3—3 of Fig. 1.

Fig. 4 is a horizontal section of one of the pump units taken on line 4—4 of Fig. 1.

Fig. 5 is a horizontal section of one of the pump units taken on line 5—5 of Fig. 1.

Fig. 6 is a horizontal section of one of the pump units taken on line 6—6 of Fig. 1.

Fig. 7 is a horizontal section of one of the pump units taken on line 7—7 of Fig. 1.

Fig. 8 is a horizontal section of my pump taken on line 8—8 of Fig. 2, showing the valved packer.

Fig. 9 is an elevation of my pump with intermediate portions thereof broken out, showing a plurality of the pump units in elevation and brought close together, and showing other parts of the pump, including the fluid-pressure chamber, in longitudinal section.

Fig. 10 is a fragmentary view of my pump, partly in elevation and partly in longitudinal section, illustrating one of the pump units.

Fig. 11 is a horizontal section of one of the pump units taken on line 11—11 of Fig. 1.

Fig. 12 is a fragmentary vertical section taken on line 12—12 of Fig. 7.

Referring more particularly to the drawings, in which corresponding parts are designated by the same reference characters in all of the figures,

my pump includes a plurality of pump units 1 connected together in spaced superimposed relation by pipes 2, a packer 3 positioned in the lower part of a well casing 4, an inlet pipe 5 connecting the lower end of the lowermost pump unit 1 to the upper side of the packer 3, an inlet pipe 6 connected to the lower side of said packer, an inlet check valve 7 positioned in said inlet pipe 6, and an outlet pipe 8 connected to the upper end of the uppermost unit 1 and extending upwardly through a casing head 9 on the upper end of the well casing 4, there being a packing box 10 in said casing head surrounding said outlet pipe 8. A fluid inlet pipe 11 extends into and is screw-seated in said casing head 9.

Each pump unit 1 includes a stator 12, a rotor 13, a slide valve 14 and a rotary pump 15 at its lower end.

The stator 12 comprises a lower member 16, a top member 17, stationary vane members 18 and 19 and a spacing sleeve 21 interposed between said stationary vane members. The lower member 16 is provided with a plurality of fluid inlets 22 near its upper end, which inlets are spaced around said member in the side wall thereof and said member is formed with an internal annular seat 25, upon which the valve 14 of the unit rests in its lowermost position while uncovering said fluid inlets 22. The lower member 16 is also formed with an axial sleeve bearing 16' extending from the lower end to the upper end of said member, on which sleeve bearing the valve 14 is slidably fitted. The top member 17 of each pump unit 1 is formed with a lower wall 26, an inner wall 27 and an outer wall 28 which converges upwardly and terminates in an upwardly-extending internally-threaded coupling 29 with which communicates the outlet 30 in said top member, there being formed in said top member 16 a plurality of annularly-spaced outlet ducts 31 forming nozzles which extend upwardly through the lower wall 26 and converge upwardly through the inner wall 27 into the outlet 30 of said top member. In the coupling 29 of each pump unit 1, except the uppermost unit, is screw-seated the lower end of one of the pipes 2, and in the coupling 29 of the uppermost pump unit is screw-seated the lower end of the outlet pipe 8. Bolt sleeves 32 are formed on the outside of the rotary pump 15, inlet valve member 16, stationary vane member 18, spacing sleeve 21, stationary vane member 19 and top member 17, respectively, through which sleeves are extended elongated bolts 33 with their heads resting upon the upper ends of the sleeves 32 on the top mem-

ber 17.

ber 17 and with nuts 33' threaded on the lower ends of said bolts and engaging the lower ends of the sleeves 32 on the pump 15, whereby the above described parts of the unit 1 are detachably held together in assembled relation. Each of the stationary vane members 18 and 19 comprises a plurality of spaced radial vanes 34 connected at their inner ends to an inner sleeve 35 and at their outer ends to an outer sleeve 36, said vanes being inclined and curved slightly to the right from their lower edges to their upper edges, as shown in Fig. 10 of the drawings. The vane member 18 is positioned upon the upper end of the lower casing member 16 with the lower ends of its inner sleeve 35 and its outer sleeve 36, respectively, resting upon the upper ends of the outer wall and the sleeve bearing 18' of said lower casing member 16. The spacing sleeve 21 is positioned upon the stationary vane member 18 with the lower end of its wall resting upon the upper end of the outer sleeve 36 of said stationary vane member. The stationary vane member 19 is positioned upon the spacing sleeve 21, with the lower end of its outer sleeve 36 resting upon the upper end of the wall of said spacing sleeve. The top member 17 is positioned upon the stationary vane member 19, with the lower end of its outer wall 28 resting upon the upper end of the outer sleeve 36 of said stationary vane member.

The rotor 13 comprises an elongated tubular journal 37 and a rotary vane member 39, which journal extends vertically through and is turnably fitted in the sleeve bearing 16', inner sleeves 35 of the stationary vane members 18 and 19 and the annular inner wall 21 of the top member 17, the rotary vane member 39 being keyed on the journal 37 by a key 40 within the spacing sleeve 21 and between the stationary vane members 18 and 19. The rotary vane member 39 comprises a plurality of spaced radial vanes 44 connected at their inner ends to a hub 42 and at their outer ends to an annulus 43 turnably fitted within the spacing sleeve 21, said hub 42 being slotted at 42' to receive the key 40 and turnably resting at its lower end upon the upper end of the inner sleeve bearing 35 of the stationary vane member 18. The vanes 44 of the rotary vane member 39 are inclined and curved slightly upwardly to the left (Fig. 10) in the opposite direction to the inclination and curvature of the vanes 34 of the stationary vane members 18 and 19.

The rotary pump 15 of each pump unit 1 is located at the lower end of the unit and includes generally a casing 44, a rotary body 45, a radial blade 46 slideably mounted in a radial slot 47 in said body, and a spring 48 located in said slot with its ends bearing respectively against the inner end of said slot and the inner end of said blade. The casing 44 is held against the lower end of the lower casing member 16 of a pump unit 1 by the bolts 38 extending through the sleeves 32, which are formed on the rotary pump casing 44, and the nuts 33' threaded on the lower ends of said bolts against said sleeves. The rotary body 45 is secured on the lower end portion of the tubular journal 37 of the rotor 13, within the casing 44 of the pump 15, which casing is positioned eccentrically with relation to said rotary body, so that the periphery of said body contacts the inner surface of the casing 44 at a point 49 diametrically opposite the blade 46. The rotary pump casing 44 is formed with a depending sleeve 50, in the upper end of which is journaled the lower end of the tubular journal 37 of a pump

unit 1, and in the lower end of which sleeve is threaded the upper end of a pipe 2, which is threaded at its lower end in the coupling 29 on the upper end of the next lower pump unit 1.

5 In the sleeve 50 is formed a duct 51 which leads upwardly from the sleeve to the pump casing 44 and communicates with an inlet 52 leading into the pump chamber 53 of the rotary pump 15 at one side of the point of contact 49 between the rotary body 45 and the casing wall of said pump chamber in the pump casing 44. From the other side of said point of contact 49 an outlet 54 leads from the pump chamber 53 into a duct 55, which leads upwardly into the lower part of the lower casing member 16 of the pump unit 1 through the sleeve bearing 16' of said casing member, for communication with a plurality of circumferentially-spaced inlet ports 56 in the tubular journal 37 of the rotor 13 of said pump unit. A check valve 57 is positioned in the tubular journal 37 below the inlets 56 to prevent fluid from flowing below said valve in said tubular journal, said valve comprising a ball 58 and its seat 59 in said tubular journal, and there being internal lugs 60 formed in said journal above the inlets 56 for arresting the upward movement of the ball 58 of the valve 57. The duct 55 has an outlet 61 leading into the lower portion of the lower unit casing member 16 below the valve 14, and the sleeve bearing 16' of said casing member is provided with a plurality of circumferentially-spaced outlets 62 adapted to register with a plurality of circumferentially spaced inlets 63 in the tubular journal 37.

35 The packer 3 comprises a rim 64, and a partition 65 extending diametrically of said rim between its lower and upper edges, which partition is formed with a depending coupling sleeve 66 and an upstanding coupling sleeve 67, and is provided with ports 68 and 69, said ports 68 extending through said partition 65 between said coupling sleeves 66 and 67 and said rim 64, and said port 69 extending through said portion and communicating at its lower end and upper end with said coupling sleeves 66 and 67, respectively. The rim 64 is formed with an annular recess 70 in which is fitted an annular rubber gasket 71 which fits the interior of the well casing 4 tightly to prevent fluid from passing upwardly from the bottom of the well between said packer rim 64 and well casing 4. The ports 68 are normally closed by ball check valves 72 resting upon seats 73 at the upper ends of said ports, and rods 74 extend over said valves between the rim 64 and the coupling sleeve 67 for limiting the upward movement of said valves. The lower end of the inlet pipe 5 is threaded in the upstanding coupling sleeve 67 of the packer 3, and the upper end of the inlet pipe 6 is threaded in the depending coupling sleeve 66. In the lower end of the inlet pipe 6 is threaded the upper end of a screen pipe 75 provided with perforations 76, which screen pipe extends down into the fluid in the bottom of the well.

65 The well casing 4, packer 3, and casing head 9 form a fluid-pressure chamber 77.

The operation of my invention is as follows: My pump is constructed and arranged so that all of the pump units 1 may be submerged in the oil in the well casing 4, assuming the well to be an oil well, below the normal or natural level of the oil, indicated 18 in Fig. 9 of the drawings. With my pump so submerged fluid under pressure, preferably compressed air or natural gas, is introduced from a source of sup-

ply through the supply pipe 11 into the upper end of the fluid-pressure chamber 77 within the well casing 4, which fluid fills the space in said chamber between the oil level 78 and the casting head 9, and the pressure of said fluid upon the oil forces the oil first through the inlets 22 in the uppermost pump unit 1 and upwardly through said unit between the vanes 34 of its lower stationary vane member 18, the vanes 41 of its rotary vane member 39, and the vanes 34 of its upper stationary vane member 19, through nozzles 31, and outlet 30 of said pump unit, and through the outlet pipe 8; whereupon the rotor 13 of said uppermost pump unit and the rotary body 45 and blade 46 of the rotary pump 15 of said pump unit are rotated, and oil is positively pumped upwardly by said rotary pump 15, the oil passing from the depending sleeve 50 of said pump through inlet duct 51, inlet 52, pump chamber 53, outlet 54, outlet duct 55, inlet ports 56, tubular journal 37 and outlet pipe 8, and as the oil is thus pumped out of the well by said uppermost unit the level 78 of the oil in the fluid-pressure chamber 77 is lowered. When the level of the oil is lowered in said fluid-pressure chamber 77 below the inlets 22 of said uppermost pump unit 1, fluid under pressure, instead of oil, from said fluid-pressure chamber 77 passes through said inlets 22 and upwardly through said pump unit and out through said outlet pipe 8, thereupon the rotor 13 of said uppermost pump unit 1 is rotated with greater velocity by the action of the fluid pressure upon the vanes of the vane members 18, 39 and 19 successively, and the fluid passing over the upper end of the rotor journal 37 aerates or gassifies the oil, which passes out of the rotor journal and outlet pipe 8, and thereby augments the lifting action of the rotary pump 15 of said uppermost unit 1. As the uppermost pump unit 1 is operated by the fluid, as aforesaid, the pressure of the fluid upon the oil in the fluid-pressure chamber 77 forces oil through the inlets 22 of the next lower pump unit 1 and upwardly through said unit and operates said pump unit in the same manner as said uppermost unit was initially operated by the oil, whereupon oil is positively lifted by the rotary pump 15 of said next lower pump unit through said unit and the pipe 2 connecting the outlet of said unit to the inlet of the uppermost unit 1, and through the tubular journal 37 of said uppermost unit and out through the outlet pipe 8, lifting the ball 58 of valve 57 off its seat 59, so that some oil will pass from said tubular journal 37 through ports 56, duct 55 and port 61 into the lower part of the lower stator member 16, and the pressure of said oil will lift the slide valve 14 of the uppermost pump unit until said valve closes the inlet ports 22 of said unit and shuts out fluid from the pressure chamber 77 into said uppermost pump unit, so that the rotor 13 of said uppermost unit will cease rotating and the oil is then lifted through the pump by said next lower pump unit 1. The pump units below said next lower pump unit are successively operated as above described to lift the oil therethrough and the lifting operations of said pump units successively discontinued as above described, as the level of the oil descends in the fluid-pressure chamber 77, until only the lowermost pump unit 1 is operated by the fluid under pressure in said pressure chamber 77, whereupon the inlet valve 7 is raised off its seat, so that oil is pumped by said lowermost pump unit from the bottom

of the well, below the packer 3, up through the pump and out through the outlet pipe 8. If the load becomes too great for the lowermost pump unit 1, any one or more of the units above the lowermost unit will automatically be operated by the fluid under pressure from the pressure chamber 77. When the pressure of the natural gas below the packer 3 in the well becomes greater than the fluid pressure in the fluid-pressure chamber 77, said natural gas opens the packer check valves 72 and enters said fluid-pressure chamber and displaces the fluid in said chamber admitted thereto through the fluid-inlet pipe 11, whereupon said natural gas enters the pump units 1 through their inlets 22 and operates said pump units for pumping the oil from the well, and during such operation of the pump the fluid admitted through pipe 11 into pressure chamber 77 may be shut off from said chamber, by closing the fluid-inlet valve 11'. When the pressure of the natural gas reduces to a point insufficient to operate the pump the check valves 72 close, so that no more natural gas is admitted into the pressure chamber 77, whereupon the fluid inlet valve 11' is opened to admit fluid under pressure into said pressure chamber to operate the pump as aforesaid. At times the natural gas may be of high pressure but reduced volume, and would not be sufficient alone to operate the pump, but may be used in combination with a reduced amount of fluid admitted into the pressure chamber 77 through the pipe 11 to operate the pump.

In case the pressure of the gas in the well becomes great enough to cause the oil to flow the oil will be forced by the gas up through the pump, whereupon the valves 57 in the pump units 1 will be opened by the oil pressure and some of the oil will pass from the tubular journals 37 through ports 56, ducts 55 and ports 61 into the lower members 16 of the pump units and said oil will lift the valves 14 and close the inlet ports 22 of the pump units, so that the pump 45 will stop running, thus allowing the oil to be delivered entirely through the pump by the natural gas pressure. When the valves 14 are raised and close the inlet ports 22 said valves uncover the ports 62 and permit oil to pass freely from under the said valves through said ports 62 and ports 63 into the tubular journals 37 and out of the pump with the oil flowing through the same under the natural gas pressure.

I do not limit my invention to the exact construction above described because various changes may be made therein without departing from the spirit of the invention.

In shallow wells one pump unit 1 only will be sufficient to pump the oil from the well.

I claim:

1. In a fluid-operated pump, a pump unit provided with an inlet and an outlet, and with inlets in its sides, said pump unit comprising a vane stator, a vane rotor, a valve resting below said inlets in the sides of the unit, and a pump within the unit for positively lifting liquid through the unit, said rotor being formed with a tubular journal rotatably mounted in said stator and communicating with said inlet and said outlet, means whereby said pump within the unit is operated by said tubular journal, the space occupied by the vanes of said stator and said rotor communicating with said inlets in the sides of the unit and with said outlet, and means for admitting fluid under sufficient pressure from

said tubular journal into the pump unit below said valve for raising said valve to close said inlets in the sides of the unit.

2. In a fluid-operated pump, a pump unit provided with an inlet and an outlet, and with inlets in its sides, said pump unit comprising a vane stator and a vane rotor, a valve resting below said inlets in the sides of the unit, and a rotary pump within the unit for positively lifting liquid through the unit, said rotor being formed with a tubular journal rotatably mounted in said stator and communicating at its ends, respectively, with said inlet and said outlet, said tubular journal being constructed and arranged to drive said rotary pump, the space occupied by the vanes of said vane stator and said vane rotor communicating with said inlets in the sides of the unit and with said outlet, and means for admitting fluid under sufficient pressure from said tubular journal into the unit below said valve for raising said valve to close said inlets in the sides of the unit.

3. In a fluid-operated pump, a pump unit provided with an inlet and an outlet, and with inlets in its sides, said pump unit comprising a vane stator, a vane rotor, a valve resting below said inlets in the sides of the unit, and a pump

within the unit for positively lifting liquid through the unit, said rotor being formed with a tubular journal rotatably mounted in said stator and communicating with said inlet and said outlet, means whereby said pump within the unit is operated by said tubular journal, the space occupied by the vanes of said stator and said rotor communicating with said inlets in the sides of the unit and with said outlet, said pump within the pump unit being formed with an inlet duct leading from said inlet of the pump unit, and with an outlet duct leading into said tubular journal, a check valve mounted in said tubular journal below said outlet duct, and means for admitting fluid under pressure from said tubular journal into the pump unit below said first valve for raising said valve and closing said inlets in the sides of the pump unit, when the fluid pressure in said tubular journal below said check valve is sufficient to open said check valve.

4. In a fluid-operated pump as claimed in claim 1: means for allowing fluid under pressure to escape from under said valve into said tubular journal when said valve has been raised, and closes said inlets.

ROY E. LEONARD.
